UNITED STATES PATENT OFFICE.

HARRY J. MALERSTEIN, OF LOS ANGELES, CALIFORNIA.

MATTRESS.

1,421,274.

Specification of Letters Patent. Patented June 27, 1922.

Application filed October 31, 1921. Serial No. 511,582.

To all whom it may concern:

Be it known that I, HARRY J. MALERSTEIN, a citizen of the United States, residing at Los Angeles, in the county of Los Angeles and State of California, have invented new and useful Improvements in Mattresses, of which the following is a specification.

My invention relates to a mattress, the principal objects of my invention being to provide a relatively simple and practical mattress, the construction thereof being such as to enable the mattress to be easily and cheaply produced, to provide a mattress wherein a fibrous body or filling retains its shape independently of the ticking or mattress covering, thereby enabling the mattress to be easily and quickly re-covered in the event that the ticking or covering becomes worn or soiled, and further to provide a mattress wherein the fibrous body or filling is provided on both faces with longitudinally and transversely disposed strips of material, the same crossing each other at regular distances apart, and the crossed members on one face of the mattress body being connected to the cross members on the other face by flexible ties that extend through the mattress body.

With the foregoing and other objects in view, my invention consists in certain novel features of construction and arrangement of parts that will be hereinafter more fully described and claimed and illustrated in the accompanying drawings, in which:

Fig. 1 is a perspective view of one of the sections of ticking that are utilized for covering the upper and lower faces of the body of the mattress.

Fig. 2 is a perspective view of the mattress as it appears during the process of manufacture, and while the tie members are being placed through the body of the mattress.

Fig. 3 is a perspective view of the mattress as it appears when finished and ready for use.

Fig. 4 is a perspective view of the mattress when the ticking or cover thereof is partially removed.

Fig. 5 is an enlarged sectional perspective showing a portion of the mattress and the tie members loosely arranged through the body thereof.

Fig. 6 is a sectional perspective showing a portion of the mattress body,--with the tie

members drawn into taut condition, and with the ends of said tie members secured to each other.

Referring by numerals to the accompanying drawings, 10, 10 designate substantial rectangular sections of ticking or like fabric that combine with an edge strip 11 to form a covering for the body 12 of the mattress, and which body is preferably composed of 65 cotton, curled hair, or analogous fibrous material.

Before the sections 10 of ticking are combined with the edge strip 11, a series of longitudinally disposed strips 13 of flexible material, preferably fabric, are arranged at equal distances apart upon the inner face of each section of ticking, and overlying these longitudinally disposed strips are transversely disposed strips 14 of suitable fabric 75 or like flexible material.

The strips 13 and 14 are secured to the section of ticking 10 by relatively short rows of stitching 15, which extend lengthwise of the strips between the points where the same 80 cross each other, and said strips are secured to the section of ticking so that there is a certain amount of fulness in said strips at the points where the same cross each other, and which fulness is designated by the nu- 85 meral 16.

Formed in each section of ticking 10, and immediately adjacent to the crossing points of the strips 13 and 14 are openings in which are located suitable eyelets 17 of metal or the like.

In the manufacture of my improved mattress the ticking or covering therefor, is made up from a pair of the sections 10, and an edge strip 11, said covering being left 95 open at one end to permit the fibrous body 12 to be inserted in the cover, and after said body has been properly arranged and packed within the cover, a suitable needle carrying a tie member, preferably a heavy 100 thread or cord, is passed through the oppositely disposed members of each pair of the eyelets 17, and through the interposed fibrous body of the mattress, and which needle and cord pass directly adjacent to 105 the side edges of the strips 13 and 14 at the crossing points thereof, and when the needle and cord is passed through the body of the members in a reverse direction, the needle is directed so that the cord passes 110 across the opposite edges of the strips 13 and 14, with the result, said strips 13 and

14 on both sections of the ticking are engaged in the loops 18 that are formed through the mattress body (see Fig. 5).

After loops 18 have thus been formed through all of the pairs of eyelets 17, said loops are drawn tightly through the body of the mattress and the ends of the portions of cord forming said loops are secured to each other by a suitable knot or 10 hitch, with the result that the portions of the strips 13 and 14 that are immediately adjacent to the crossing points, are drawn into the fibrous body of the mattress as shown in Fig. 6, thereby retaining said 15 fibrous body firmly in proper shape, and without depending on the covering members or sections 10 of ticking.

In the event that the mattress covering becomes worn or soiled, and it is desired 20 to re-cover the mattress, the rows of stitching 15 are cut or broken so as to permit the sections 10 to be removed from the mattress body, as illustrated in Fig. 4, and said mattress body when thus uncovered will 25 retain its shape by virtue of the tie members which pass through said mattress body and engage the crossed flexible strips 13 and 14.

A mattress of my improved construction 30 may be easily and cheaply produced, is capable of being easily and quickly recovered, and the body of the mattress is effectively reinforced so that it will always retain its original shape.

One of the particular advantages gained 35 by my improved construction, is that the covering of the mattress may be cut to the exact length and width of the completed mattress, and in this connection it will be understood that in a mattress of ordinary 40 construction, the covering must be cut considerably longer and wider than the completed mattress in order to provide for a sufficient amount of excess material that 45 is taken up or drawn together when the mattress body is tufted in the usual manner.

The crossed stay members 13 and 14 that are applied to both faces of the mattress body or filling, provide a flexible skeleton 50 framework for said mattress body, and

such construction in addition to firmly retaining the body in shape, imparts to it the desired flexibility and resiliency.

It will be understood that minor changes in the size, form and construction of the 55 various parts of my improved mattress, may be made and substituted for those herein shown and described, without departing from the spirit of my invention, the scope of which is set forth in the appended claims.

I claim as my invention:

1. In a mattress, a pair of covering members, crossed strips of flexible material secured to the inner face of each covering member, there being openings formed in the covering members at points corresponding to the crossing points of said strips, a body of fibrous material between the covering members, and tie members connecting 65 the crossed portions of the covering members on one side of the mattress body to the crossed portions of the strips on the other covering members.

2. In a mattress, a pair of flexible mattress sections, cross strips of flexible material secured to the inner faces of said cover sections, a body of fibrous material between said cover sections, loops of cord passing through said fibrous body and engaging said flexible strips at the points where 70 the same cross each other, and there being openings formed in said cover sections adjacent to the points where the flexible strips cross each other.

3. A mattress comprising a pair of flexible covering sections, a body of flexible material between the cover sections, cross strips of flexible material secured to the confronting faces of the sections, eyelets in 90 the sections at points corresponding to the intersection of the strips, and loops of cord extended through the strips at the points of intersection and drawn to effect compression of said body at points corresponding 95 to the eyelets.

In testimony whereof I have signed my name to this specification.

HARRY J. MALERSTEIN.
